MULTIPLE COMBINED STACK AND INDIVIDUAL WASTE AND GROUP VENTING ASSEMBLY

William C. Groeniger, Columbus, Ohio, assignor to
 John B. Pierce Foundation, New York, N. Y.,
 a corporation of New York

Application October 27, 1939, Serial No. 301,577

2 Claims. (CL. 4-211)

My present invention relates to improved multiple combined stack and individual waste and group venting assemblies.

My present invention provides main stack and sub-main stack piping for the discharge, with group venting of groups of plumbing fixtures disposed on floor levels of a building structure, each group comprising a plurality of plumbing fixtures disposed on any given floor level, the multiple groups being disposed on the respective floor levels in substantial vertical alignment.

My invention provides for the locating of the desired particular plumbing fixtures on any given floor level in any position mutually with respect to one another as desired, the individual plumbing fixtures being disposed optionally at any radial location, the soil pipe stack and main vent stack serving as the center. Preferably, each plumbing fixture is connected by individual waste branch with the waste and venting assembly of its floor level.

In preferred embodiments of my invention, each waste and venting assembly for any given floor level comprises a fitting disposed at and extending through the floor level, such fitting comprising laterally extending channels, the termini of which are disposed above the floor slab and arranged to be connected with waste branches of plumbing fittings on such floor level.

Further features and objects of the invention will be more fully understood from the following detail description and the accompanying drawings, in which

Fig. 1 is a horizontal sectional view on line 1—1 of Fig. 2.

Fig. 2 is a vertical elevation illustrating a typical embodiment of my multiple combined stack and individual waste and group venting assembly at a floor level.

Fig. 3 is a side elevation of Fig. 2, viewed in a plane at right angles to that of Fig. 2.

Fig. 4 illustrates diagrammatically in vertical section the application of my invention to a four-story building.

Fig. 5 is a detail sectional view on line 5—5 of Fig. 4.

Fig. 6 is a detail sectional view on line 6—6 of Fig. 4.

Fig. 7 is a vertical central sectional view of an upperly fitting shown in Figs. 2 and 3.

Fig. 8 is a vertical central sectional view of a lowerly fitting shown in Figs. 2 and 3.

Referring to Figures 1, 2, 3 and 4, the last named indicating diagrammatically the application of my invention to a four-story building, I

provide main stack piping designated 10, the upper terminus 10a of which communicates with the outer atmosphere; its lower terminus 10b is suitably connected with soil piping 11 leading to a sewer or equivalent disposal means.

The first floor level is indicated at 12, the second floor level at 12a, the third floor level at 12b, the 4th floor level at 12c, the ceiling of the uppermost floor is indicated at 13 and the roof at 14. The main stack 10 is shown extending through the ceiling 13 of the uppermost story and the roof 14.

In preferred embodiments of my invention the waste and venting assemblies indicated generally 15 may be of substantially duplicate construction. As illustrated in greater detail in Figs. 1, 2 and 3, each waste and venting assembly comprises a fitting 16, advantageously disposed at and extending through the floor level at which it is located, as for example the second floor level 12a. Such fitting comprises a through channel 16a which communicates through its upper terminus with the upper reach of the main vent stack piping 27, preferably through a fitting 17. The fitting 16 comprises further laterally extending channels 16b, 16c, the termini of which are disposed above the floor slab and connected with waste branches of plumbing fixtures serving the waste and venting assembly, and preferably draining at 20 relatively low level. Typical of such low level draining plumbing fixtures I have illustrated a toilet bowl 18, the waste branch 19 of which is shown, see Fig. 2, as connected with the terminus of the lateral channel 16b of the fitting 16. A bath tub 20 (or shower or equivalent) may similarly be connected by a waste branch 21 with the terminus of the laterally extending channel 16c of the fitting 16. A trap 20a is indicated for such plumbing fitting.

Such fitting 17, see Figs. 1 and 3, is advantageously employed for the discharge and venting of any plumbing fixtures draining at a relatively high level and for such purpose is provided with laterally extending channels 17a, 17b, the former being connected, for example, to a waste branch 22 of a lavatory 23. The terminus of the laterally extending channel 17b may be connected to a waste branch 24 of a kitchen sink 25 or laundry tub or equivalent. A lavatory, a kitchen sink, laundry tub and the like are typical of plumbing fixtures draining at relatively high level.

The lower terminus of the fitting 16 is suitably connected to the main stack 10 as by an appropriate fitting 26, see Figs. 2, 3 and 4, for the dis-

charge of the fixtures from the waste branches 19, 21, 22, and 24.

In the preferred embodiment indicated in Fig. 4, the main vent stack is denoted by the reference number 27, which excepting for the first floor, extends through the respective floor levels and is suitably connected at its upper terminus, as by a suitable fitting 28, with an uppermost portion of the soil pipe stack 10. The lower terminus 27a of the main vent stack 27 is suitably connected as by piping 29, to the upper terminus of the fitting 17 of the waste and venting assembly of the first floor, and communicates through such fitting 17 and therewith through the fitting 16 and fitting 26 with the lower portion 10b of the soil pipe stack.

Referring to Figs. 2 and 3, and also Figs. 5 and 6, with respect to the waste and venting assemblies of the second and upper floor levels, the upper terminus 17c of the fitting 17 is connected by a pipe 30 or equivalent to a fitting 31 to afford communication of the same with the main vent stack 27. Fig. 7 illustrates in central vertical section a typical formation of such fitting 31. Fig. 8 illustrates in central vertical section a typical formation of the fitting 17. Fig. 8 illustrates also the general formation of the fitting 16.

Preferably at each floor level, the soil pipe stack 10 and main vent stack 27 and the waste and venting assembly of such floor level are enclosed in a suitable casing the walls of each casing advantageously extending from the floor slab to the ceiling; removable closures of suitable openings in such casing walls are provided for affording access for inspection and repair.

At the respective floor levels, the positions of the group of plumbing fixtures, typified by toilet bowl 18, bath tub or shower 20, lavatory 23, kitchen sink or laundry tub 25, may be varied as desired or required with respect to the soil pipe stack 10 as a center. Also, preferably, each plumbing fixture is provided with a waste branch individually connecting such fixture with the waste and group venting assembly of its floor level, i. e., independently of any other plumbing fixture. Group venting of the plumbing fixtures at each floor level is thus afforded by its independent branch waste connection with its associated waste and venting assembly through the main vent stack 27 in cooperation with the soil pipe stack 10, thereby insuring full flow of discharge of the plumbing fixtures singly or plurally at all times at any given floor level and concurrently at any two or more floor levels.

In compliance with code regulations, suitable cleanout inspection and repair may be provided at any convenient location, such as at the flooring 32 of the flooring basement or equivalent, as is indicated at 33.

The respective fittings serving as component parts of my combined stack and multiple waste and venting assemblies preferably embody the construction of my U. S. Patent No. 2,065,523, dated December 29, 1936, entitled Methods of uniting fluid streams and devices therefor.

Water closets of the type set forth and claimed in my U. S. Letters Patents Nos. 2,066,881 and 2,066,882, both granted on January 5, 1937, and in subsequently granted patents, are particularly applicable in connection with the instant invention, in that the discharge of the same through the selected branch waste piping is disposed above the floor level.

The present invention affords also the assembly as a unit of the casing and therein en-

closed soil and vent piping, water distribution lines and the like, suitably supported in the casing. Such unitary assembly may be completed prior to installation for delivery on the job, thus affording all-year-round work for labor, facility of installation, certainty of proper assembly of individual parts, certainty of leak-proofness of joints, and other advantages.

As appears from the above, the invention affords the installation of a plumbing system, including selective positioning relative to one another of the desired individual plumbing fixtures, within a building structure, the main soil and vent piping and therewith associated water lines and the like being disposed spaced from the walls of the building structure. By the provision of the casing, all soil and vent stacks and all water distribution piping and therewith connected parts are concealed from view, while at the same time optimum access is afforded to such enclosed parts. Such arrangement simplifies the insulation of such piping thermally and particularly for reduction of noises ensuing in the flow of supply water and aqueous discharges.

Whereas I have described my invention by reference to specific forms thereof, it will be understood that many changes and modifications may be made without departing from the spirit of the invention.

I claim:

1. In a multiple story building, the combination of a soil pipe stack having its upper terminus in communication with the outer atmosphere, a vent stack connected at its upper terminus with the soil pipe stack and extending through a plurality of floor levels, waste and group vent assemblies for said floor levels disposed above the respective floor levels, each waste and venting assembly comprising a fitting extending through its floor level and communicating through its lower terminus with said soil pipe stack and through its upper terminus with said vent stack, said fitting having laterally extending channels the termini of which extend above the floor level, a fitting disposed above said first-named fitting and communicating with said first-named fitting, said second-named fitting communicating with said vent stack, said second-named fitting having laterally extending channels, and waste branches each disposed above the level of its floor connected to the respective termini of said laterally extending channels for the discharge of plumbing fixtures on the respective floor levels, said soil pipe stack and said vent stack being disposed within the walls of the building and in spaced relation thereto.

2. In a multiple story building, the combination of a soil pipe stack having its upper terminus in communication with the outer atmosphere, a vent stack connected at its upper terminus with said soil pipe stack and extending through a plurality of floor levels, individual waste and group vent assemblies for said floor levels respectively, each waste and group vent assembly comprising a fitting extending through its floor level and communicating through its lower terminus with said soil pipe stack and through its upper terminus with said vent stack, said fitting having laterally extending channels the termini of which extend above the floor level, a fitting disposed above said first-named fitting and communicating with said first-named fitting, said second-named fitting communicating with said vent stack, said second-named fitting having laterally extending channels, the laterally ex-

tending channels of said second-named fitting extending in directions angularly intermediate the directions of extension of the lateral channels of said first-named fitting, and waste branches disposed wholly above the respective floor levels connected to the respective termini of

said laterally extending channels for the discharge of plumbing fixtures on the respective floor levels, said soil pipe stack and said vent stack being disposed within the walls of the building and in spaced relation thereto.

WILLIAM C. GROENIGER.
